ELECTRIC CHARCOAL LIGHTER

Howard L. Bourner, Nashville, Tenn., assignor to Edwin L. Wiegand Company, Pittsburgh, Pa.

Filed June 2, 1965, Ser. No. 85,548

Term of patent 14 years

(Cl. D81—10)

I claim:

The ornamental design for an electric charcoal lighter, substantially as shown.
